UNITED STATES PATENT OFFICE.

FREDERICK MORGENSTERN, OF MCKEES ROCKS, PENNSYLVANIA.

OIL-WELL PUMP.

No. 918,460.

Specification of Letters Patent.

Patented April 13, 1909.

Application filed July 10, 1908. Serial No. 442,950.

To all whom it may concern:

Be it known that I, FREDERICK MORGENSTERN, residing at McKees Rocks, in the county of Allegheny and State of Pennsylvania, have invented certain new and useful Improvements in Oil-Well Pumps, of which the following is a specification.

This invention, which relates generally to improvements in oil well pumping means, 10 more particularly has for its object to provide an improved construction of the piston portion of the pump, of a simple and economical character that can be readily adapted for use in connection with the ordinary 15 types of pumping mechanisms, and which, when adjusted for use, does not easily become out of order, broken or worn, and effectively serves its intended purposes.

In that type of pumps in which the piston rod end has expandable packing rings, especially when of leather, by reason of the fine sand, grit and other sediment that lodges under and between the rings, the said rings become worn so fast that they usually have 25 to be replaced every other day. To overcome this objectionable feature, that of almost daily pulling out the piston and the consequent loss in the operation of the pump, I have provided a piston rod end construction 30 for pumps that comprehends an elongated tubular piston member having the usual caged valve at the upper or outlet end, a plurality of expansion rings mounted thereon but held separated by members, tightly 35 but removably, held on the tubular piston body that have collecting spaces or pockets that take up the sand and grit and relieve the expansive rings of the grinding or sticking action, such as occurs when the sand or 40 grit settles back of or between the expansive rings.

My invention, in its more subordinate features consists in certain details of construction and peculiar combination of parts, 45 all of which will be hereinafter explained, specifically pointed out in the appended claims and illustrated in the accompanying drawings, in which:—

Figure 1, is a side elevation of an oil well 50 pump piston, embodying my invention. Fig. 2, is a vertical section of the same. Fig. 3, is a perspective view of the lower end of the piston, with the coupling nut and the lower 55 set of expansion rings removed. Fig. 4, is a perspective view of the tubular piston body

with the valve and cage attached to the upper end thereof. Fig. 5, is a vertical section, parts being in perspective of one of the sediment holding cylinders. Fig. 6, is a horizontal section taken substantially on 60 the line 6—6 on Fig. 2. Fig. 7, is a similar view on the line 7—7 on Fig. 2.

In the practical arrangement of my invention, the tubular piston body 1 may be of the conventional length, its upper end having 65 an annular seat 10 that merges with the nut or wrench receiving portion 11, that has the usual threads 12 for receiving the threaded end 20 of the cage 2 that carries the ball 70 valve 3 in the usual manner that works 70 against a valve seat *a* in the upper end of the rod 1 as clearly shown in Fig. 2.

Loosely mounted on the annular union nut 7 is a collar 4 upon which is mounted one or more split packing rings 5—5, the 75 number of said rings depending on the height of the collars 4 in the present showing two rings being provided, the combined height of which equals the height of the collar 4. Other collars 4^a—4^b are mounted 80 on the tubular piston body and these are held at proper intervals by spacing cylinders or sleeves 6—6^a, the lower one of which rests on the lower set of collars and supports the collar 4^a at its upper end and also the 85 second set of split packing rings 5^a—5^a that fit around the collar 4^a. Mounted on the second set of rings 5^a is the upper casing or sleeve 6^a, on the upper end of which rests the third collar 4^b and the third set of expansion packing rings 5^b which are held 90 down to their seat by the annular flange 10 of the body 1 located at the upper end thereof.

While I have shown two casing sections 95 and three sets of split or packing rings, it is manifest a greater or less number of said parts may be used as may be found desirable.

Under the expansive or normal conditions 100 the rings 5—5^a—5^b are of a diameter slightly greater than that of the sleeves 4—4^a as to provide the necessary tight frictional contact with the well tubing, as clearly shown in Figs. 1, 2 and 3.

As heretofore stated, in the general type 105 of oil well pumps, the packing or sucker head rings, either leather or metal, become more or less incapacitated for use, almost daily, by reason of the sand or grit getting 110

in between the packing rings and the body of the piston head, when leather, cutting and quickly wearing them out when of metal spreading the split rings to such extent that 5 they frequently stick in the well tubing and thereby makes the pumping action ineffect-
ive.

In my construction of pump, I have provided especial means for overcoming the 10 objectionable features noted, by providing one or more pockets or receiving members that take up the spaces between the set rings which collect the sand and sediment that works in behind and under the rings, 15 said spaces in the construction shown being of sufficient area that the pumping or sucker head with the packing rings can be used for months before the said spaces need emptying.

20 The receiving spaces X are formed by making the upper portion of the sleeves 4-4^a of greater diameter than the tubular rod on which they fit and for a proper setting of the said upper ends they have internal vertical ribs 4^c that bear on the body.

The ribs 4^c extend down some distance from the top of the sleeve and do not extend the full depth of the space whereby the said space will have a full annular area to 30 form a large pocket portion for receiving the sand and grit that trickles down between the ribs 4^c. To provide for the free entry of the gritty substances into the pockets in the sleeves, the thickness of the collars 4-4^a 35 and the enlarged diameter of the upper ends of the sleeves are relatively such that when the collars are fitted upon the upper end of the sleeve, slots or openings y-y located outside of the collars 4-4^a are provided, as 40 clearly shown in Fig. 2, the slots being sufficiently large to allow the grit and sand back of and between the packing rings running down through the slots y-y.

From the foregoing description, taken in 45 connection with the accompanying drawings, the advantages and the complete construction will be readily understood.

By reason of combining the parts as shown and described, the pumping head can 50 be readily taken apart to provide for clearing the sleeves 4-4^a-4^b of the sediment collected therein.

Since ample means are provided for the escape of the sand and other gritty matter 55 from behind and between the split ring it follows that danger of their sticking by reason of being clogged by sand or becoming worn by sand rubbing is reduced to the minimum.

60 Having thus described my invention, what I claim is:

1. In a pump, in combination with a tubular piston body and packing rings mounted thereon; of sand collecting means mounted on the body, in communication with the 65 fluid spaces between the rings and the body.

2. In a pump, the combination with the piston body and packing rings mounted thereon, of sand collecting means removably mounted on the body and in communication 70 with the fluid spaces between the rings and the body.

3. In an oil well pump, the combination with the piston body, a series of packing rings mounted thereon, casings removably 75 mounted on the body, the ends of which have bearing on the packing rings, said casings having sand collecting chambers in communication with the fluid spaces between the rings and the body. 80

4. In an oil pump, the combination with the tubular piston body, a series of expansible rings mounted on the body, casings mounted on the body, and whose ends engage the expansible rings, each of said casings having a pendentively extended sand collecting chamber whose upper end is in communication with the fluid spaces between the expansible packing rings mounted upon the said end. 85

5. In an oil well pumping means of the character described, in combination with the tubular piston body section, having a valve holding cage mounted at the upper end thereof, and a coupling member at the lower end thereof; of a series of sleeves loosely mounted on the body, a series of casings loosely mounted on the body between the said sleeves, each of said casings having a pendent sand receiving pocket whose opening at the upper end of the sleeve extends beyond the peripheral edge of the loose sleeves and packing members mounted on the sleeve between the pocket equipped casings. 95

6. In a pump of the character described, the combination with the tubular piston body and the sleeve loosely mounted thereon, one or more expansible packing rings mounted on the sleeve and a casing loosely mounted on the body having radial grooves extending vertically downward from the upper end and an internal transverse groove that connects with the vertical grooves, the vertical groove being of such depth as to 115 provide openings at the upper end of the casing beyond the periphery of the sleeve. 110
